UNITED STATES PATENT OFFICE

PHILIP M. MILLER, OF CLEVELAND, OHIO

DESIGN FOR A WHEEL FOR VEHICLES

Application filed May 9, 1931. Serial No. 39,786. Term of patent 14 years.

To all whom it may concern:

Be it known that I, PHILIP M. MILLER, a citizen of the United States, residing in Cleveland, in the county of Cuyahoga and the State of Ohio, have invented a new, original, and ornamental Design for a Wheel for Vehicles, of which the following is a specification, reference being had to the accompanying drawings, forming a part thereof.

Figure 1 is a front elevational view of a wheel for vehicles showing my new design, and

Fig. 2 is an outline of the outboard side of the spider portion of the wheel.

I claim—

The ornamental design of a wheel for vehicles substantially as shown.

PHILIP M. MILLER.
